DESIGN FOR A TABLE OR LIKE ARTICLE

Edward A. Schaffer, Springfield, Mass., assignor to Hampden Specialty Products, Inc., Easthampton, Mass., a corporation of Massachusets

Application January 11, 1938, Serial No. 74,204

Term of patent 3½ years

To all whom it may concern:

Be it known that I, Edward A. Schaffer, a citizen of the United States, residing at Springfield, in the county of Hampden and State of Massachusetts, have invented a new, original, and ornamental Design for a Table or Like Article, of which the following is a specification, reference being had to the accompanying drawing, forming part thereof.

Fig. 1 is a perspective view of a table showing my new design; and

Fig. 2 is a front elevational view of the table shown in Fig. 1.

I claim:

The ornamental design for a table or like article, as shown.

EDWARD A. SCHAFFER.
